J. S. STANLEY

CLOSURE FOR RECEPTACLES

Filed Nov. 18, 1925

Patented May 8, 1928.

1,669,216

UNITED STATES PATENT OFFICE.

JAMES S. STANLEY, OF GREAT NECK, NEW YORK.

CLOSURE FOR RECEPTACLES.

Application filed November 18, 1925. Serial No. 69,722.

This invention relates to a closure for receptacles. It comprises a cap for tubes, bottles, containers and the like. It relates more particularly to a cap that can be quickly and easily placed on the receptacle for closing it and taken off for opening it, and at the same time the cap is retained in connection with the receptacle, so that the same will not become entirely detached or lost even when the cap has been removed to open the receptacle. The cap can be placed on the receptacle to close the same by being merely moved into snug closing position and frictionally held there so as to be easily removed, or, the cap can, when desired, be tightened so as to avoid inadvertent removal from the closed position.

The invention will be understood from the description in connection with the accompanying drawings, in which Fig. 1 is a side view of a receptacle and the cap in closed position; Fig. 2 is a similar view in open position; Fig. 3 is a similar view with the tube turned 90 degrees from the position shown in Fig. 1; Fig. 4 is a view similar to Fig. 3 with the cap turned 90 degrees; Fig. 5 is a plan view of the cap; Fig. 6 is a side view of the same; and Fig. 7 is a side view taken 90 degrees from Fig. 6.

In the drawings reference character 1 indicates a receptacle which may be a tube, bottle, can or the like, which is provided with a neck 2. A groove 3 extends circumferentially along the neck 2 and may be provided with arcuate portions 4 on opposite sides of the neck. The groove 3 extends from the middle of the arcuate portion on each side so as to form a screw thread on each side of the neck of a length preferably greater than one-quarter of a turn. The groove is shown as extending from the middle of the arcuate portions 4 circumferentially more than 90 degrees to the points 5. The upper sides 6 of these screw-thread portions constitute cam surfaces, the function of which is to be described more in detail hereinafter. The screw-thread portions of the groove may terminate at 5 on both sides, but will preferably extend upwardly (Fig. 3) from the points 5 to the middle of the arcuate portions 4, so that the ends of the arcuate portions 4 join the screw-thread portions at 5 on both sides, as shown in Fig. 1, at 7, on one side. The groove 3 is thus seen in the illustrated embodiment of the invention to

be made up of two screw-thread portions of about one-third of a turn on opposite sides of the neck, the upper end of each one being joined to the lower end of the other one by the more abrupt portions 7.

The cap 10 has a rounded top 11 and a depending flange so as to provide an inside hollow portion 12 into which the neck 2 of the receptacle can project. The hollow portion 12 is preferably internally threaded, as shown at 13, so that a washer 14 of resilient material, such as cork or rubber, for instance, can be conveniently retained therein. Extensions 15 are provided on opposite sides of the cap 10 which have grooves 16 extending thereacross. A portion of the flange, as shown at 17, serves as a stop when the cap is swung into closed position. A cap may be made of any appropriate material, such as tin and when so made, can be pressed or stamped into shape.

The member 20 for the cap which may be made of wire or a metal rod of any convenient cross-sectional shape, may be made of U-shape and has its two side portions 21, as seen from the side, of such shape as to adapt it to move in the groove 3 in the neck 2. The sides 21 may be connected by a curved portion 22 (Fig. 3) which may be turned upwardly slightly relative to the portions 21, as shown most clearly in Fig. 2. The member 20 extends outwardly in opposite directions from the ends of the side portions 21 to form arms 23 (Fig. 3), which cooperate with the grooves 3 to hold the cap in place, the ends of which are bent upwardly into extensions 24 that are firmly secured in the grooves 16 of the cap 10 so as to make the member 20 and cap 10 rigid with respect to each other.

The operation is as follows: In closing the receptacle, the cap 10 is moved so that the portions 21 slide longitudinally in the groove 3, until that portion of the depending flange 17, operating as a stop, contacts with the neck 2 and stops further motion. The end of the neck portion may be made sloping, as indicated at 25 (Fig. 2), so that the washer 14 will be bent slightly so as to be concave on its lower side and will come to rest on the end of the neck portion, as shown in Figs. 1 and 3. The lower edge 26 of the narrow portion of the flange of the cap 10 will be on a level with the end 27 of the neck so that that portion of the flange 110

of the cap clears the end 27 of the neck when the cap is moved sidewise.

The frictional engagement of the parts will serve to retain the cap in the desired closed position satisfactorily for ordinary uses. However, when it is desired to fasten the cap very securely upon the container, it is first moved to the closed position, as above described, and is then given a portion of a turn circumferentially, thus causing the upper and inner sides of the arcuate portions 21 near the arms 23 to ride along the cam surfaces 6 of the screw-thread portions of the groove, thus causing the cap to travel downwardly and bring its flange 26 below the end of the tube while pressing the washer 14, as shown in Fig. 4. In opening the container from this position, it is necessary first to turn the same circumferentially thus, as it were, initially unscrewing the same after which it can be pushed transversely across the neck to open the container, as above described, and the curved portion 22 of the member will contact with the side of the neck to limit the extent of the travel of the cap in the open position.

I claim:

1. In a device of the character described, a receptacle having a neck portion with a groove on opposite sides thereof, a cap having a member extending at an angle to the axis of said cap adapted to slide in said grooves longitudinally of said member.
2. In a device of the character described, a receptacle having a neck portion with a transverse groove on opposite sides thereof, a cap having a member extending at an angle to the axis of said neck portion adapted to slide longitudinally of said member in said grooves.
3. In a device of the character described, a receptacle having a neck portion with a groove on opposite sides thereof, a cap having a member extending at an angle to the axis of said neck portion rigidly attached thereto, said member being adapted to slide in said grooves longitudinally of said member.
4. In a device of the character described, a receptacle having a neck portion with a thread on opposite sides thereof, a cap having a member extending at an angle to the axis of said neck portion adapted to slide in said threads longitudinally of said member.
5. In a device of the character described, a receptacle having a neck portion with a thread on opposite sides thereof, a cap having a member extending at an angle to the axis of said neck portion adapted to slide

in said threads longitudinally of said member and also to turn in said threads.

6. In a device of the character described, a receptacle having a threaded neck portion and a cap having a member extending at an angle to the axis of said neck portion which operates in said threaded portion, said member preventing said cap from becoming detached from said receptacle. 65

7. In a device of the character described, a receptacle having a threaded neck portion and a cap having a member which slides in said threaded portion longitudinally of said member, said member extending at an angle to the axis of said neck portion preventing said cap from becoming detached from said receptacle and tightening said cap on said receptacle. 75

8. In a device of the character described, a cap having a member extending at an angle to the axis of said neck portion rigidly connected thereto, a receptacle having a neck portion provided with means whereby a sliding motion of said member longitudinally of said member places said cap on and off of the end of said neck portion. 85

9. In a device of the character described, a cap having a member extending substantially at right angles to the axis of said cap and rigidly connected thereto, a receptacle having a neck portion, said cap and neck being provided with means whereby said cap can be tightened on said neck portion by turning said cap. 90

10. In a device of the character described, a cap having a member extending substantially at right angles to the axis of said cap and rigidly connected thereto, a receptacle having a neck portion, said cap and neck portion being provided with means whereby longitudinal motion of said member opens and closes said receptacle and a transverse motion of said member tightens said cap on said neck portion. 95

11. A bottle cap having a member rigidly attached thereto on opposite sides thereof and extending at an angle to its axis. 100

12. A bottle cap having a member rigidly attached thereto on opposite sides thereof and extending at an angle to its axis, portions of said member crossing the lower edge of said cap. 105

13. A bottle cap having a member rigidly attached thereto on opposite sides thereof and extending at an angle to its axis, said member being adapted to guide said cap to open and closed position, and tighten said cap upon a receptacle. 110
